UNITED STATES PATENT OFFICE.

ISAAC C. POPPER, OF NEW YORK, N. Y.

AUTOMATIC BUTTER-CUTTING MACHINE.

1,424,117.

Specification of Letters Patent. Patented July 25, 1922.

Application filed April 23, 1921. Serial No. 463,851.

To all whom it may concern:

Be it known that I, ISAAC C. POPPER, residing at New York city, in the county of New York and State of New York, a citizen of the United States, have invented certain new and useful Improvements in Automatic Butter-Cutting Machines, of which the following is a specification.

My invention relates to an improvement in 10 automatic butter cutting machines.

While, as the name implies, this invention is designed primarily to shape and cut butter, it obviously might be used for cutting various other materials in a plastic state, 15 such as yeast, chocolate, and the like.

The present machine is arranged to work automatically, and its speed and action are controlled by the feed of the material into the machine.

20 The primary object of this invention is to cut butter or other plastic material automatically into cakes of the proper predetermined size and length, so that each cake is of uniform size and weight.

25 This cutting machine may be attached to any type of forming machine that is now in use, and it is so constructed and adapted that its capacity for fashioning and cutting the material is only limited by the volume and 30 speed with which the material can be fed to the machine.

In the accompanying drawings:

Fig. 1 is a view in side elevation of the 35 complete machine in operative position;

Fig. 2 is a side view of the wheel or cutter-head;

Fig. 3 is a front view of the same;

Fig. 4 is a fragmentary detail of the wheel or cutter-head showing the slot in the rim 40 where the knife-holder fits;

Fig. 5 is an edge view of the knife-holder;

Fig. 6 is a view of the same;

Fig. 7 is a view of the knife;

Fig. 8 is a view of the knife-holder lock-45 pin;

Fig. 9 is an enlarged fragmentary view of a portion of the rim of the wheel or cutter-head, showing where the lock-pin enters.

Fig. 10 is a view of one of the knife-holder 50 stop-bolts which limits the backward drop of the knife-holder;

Fig. 11 is a detached view of a spring for holding the knife-holder;

Fig. 12 is a front view of the cam roller 55 and arm;

Fig. 13 is a side view of the same;

Fig. 14 is a side view of the cam; Fig. 15 is a transverse sectional view through the same;

Fig. 16 is a perspective view showing the 60 name-plate;

Fig. 17 is a view in side elevation, partly broken away and in section, of the feed mechanism.

Fig. 18 is a side view of the heater hood; 65

Fig. 19 is a front view of the same or taken at right-angles to Fig. 18;

Fig. 20 is an enlarged fragmentary perspective view looking into the former and showing a knife in operative position. 70

Fig. 21 is a plan view, partly in section, of the former for regulating the transverse dimensions of the butter.

Fig. 22 is a view of the former viewed 75 from the left in Fig. 21.

A, represents the table mounted on suitable legs, and 1 is an A-shaped standard of which there are two securely bolted on the top of the table.

A shaft 2 extends across from standard to 80 standard, with its ends supported and secured in blocks 3. These blocks are fitted to, and vertically adjustable in, slots 4 by means of set-screws 5 and 6 threaded in the standards above and below each block. By means 85 of these set-screws 5 and 6, it is possible to set the wheel or cutter-head a little higher or lower on the supporting standards as may be required for the best results.

A wheel or cutter-head 7 is mounted to 90 turn on shaft 2 on roller-bearings (not shown), and a cam 8 is rigidly secured on the shaft in the position indicated in Fig. 1.

A plurality of knives 9 are spaced at predetermined intervals at the rim of the wheel 95

7. These are detachably secured to knife-holders 10 by screws or other means, and they are pivotally mounted by means of the knife-holder lock-pins 11, which are securely fastened in the slots 12 shown in 100 Fig. 4 in the rim of the wheel. The knife-holders fit in these slots, and the lock-pins hold them in place and permit the holders to turn as required.

The swinging movement of the knives 105 and knife-holders is controlled by cam-rollers 13 at the outer ends of the arms 14. These arms are securely bolted to the knife-holders, as shown in Fig. 1, and the rollers are in position to engage and traverse the 110 edge of the cam 8 presented thereto, as the wheel 7 revolves.

Springs 15 extend from the knife-holders back to a point on the wheel for holding the knife-holders yieldingly in their normal position to resist the reverse movement 5 impact to the knife-holders by the action of the rollers 13 against the edge of the cam 8.

A knife-holder stop, in the form of a bolt 16, is secured to each holder for the 10 purpose of limiting the backward movement of the knife-holder.

While there may be any number of these knives or cutters, in the present construction I have illustrated thirteen, and these 15 with their attachments are all alike, and they operate upon the butter or plastic material being formed or cut in turn successively as the wheel 7 is turned. The wheel 7 is turned by the feed of the material to 20 be fashioned and cut. A former 17 is located at one end of the table. In this one or more (preferably two) worms 18 continuously revolve. The butter or other material is fed down through a hopper (not 25 shown) from a point above into the former, and is forced out through a head 19 upon a series of rollers 20 (of which there may be any number, although in the present machine I have shown nine) on their way 30 to the knives or cutters. The head is so shaped that it gives the proper transverse dimensions to the butter or other material being fed therethrough, whereas the knives cut it into lengths, and the wheel 7 is driven 35 by the force of the on-coming material against the knives, and the speed is regulated entirely according to the feed of the material. The motion of the wheel is resisted only by the contact of the cam rollers 40 13 upon its periphery, and the periphery of the cam is shaped to give direction and position to the knives at the proper time and place in the rotation of the wheel, the cutting in this instance being done over the 45 seventh roller of the series of nine, thus leaving two more rollers for conveying the cake of material forward onto the conveyor-belt 21 at the outlet of the machine.

To facilitate the cutting of the butter, the 50 knives are heated; and this is done by their passage through a heater-hood 22, which preferably covers about one-fourth of the rim of the wheel. This is secured to the standards and straddles and embraces the 55 rim of the wheel, and it may be heated by electricity, gas, or other means. In the construction illustrated, it is heated by a resistance coil 23, as shown in Figs. 1 and 19.

60 Name-plates 24 are attached to the rim of the wheel or cutter-head. Each name-plate is preferably attached by means of two screws to the rim of the wheel or cutter-head between the knives, in order that each 65 cake of butter or other material may be

marked as it is fashioned and cut in passing through the machine.

This machine will cut the butter or other material in any size or shape. The former head 19 gives the proper height, width and 70 shape to the material, while the knives cut it into lengths.

The cakes of butter thus formed in this particular machine are in the neighborhood of one and eleven-sixteenths ($1\frac{11}{16}$) inches 75 in height, by three and one-eighth (3 $\frac{1}{8}$) inches in width, and the cakes are cut six and three-eighths (6 $\frac{3}{8}$) inches long in order to make them in pound sizes, but the knife blades can be adjusted to vary the 80 size of the cake if desired. While there are thirteen knives shown on the wheel or cutter-head, thus cutting thirteen cakes of butter with each revolution of the wheel or cutter-head, if it were desired to cut the 85 material in three inch lengths, there could be double the number of knives, thus cutting twice as many lengths per revolution.

The knives, knife-holders, wheel or cutter-head, are all securely fastened, making 90 it easy to clean the machine. The machine can be cleaned thoroughly by turning a hose with hot water over all parts with the exception of the electric heater which can be easily removed.

This machine requires no attendants, and it will cut from ten to three hundred cakes of butter per minute. In other words, it will cut approximately five times as many cakes as the machines heretofore in use, 100 which required from two to three persons per machine to operate; or in other words it will cut the butter as fast as it can be delivered through the former and former-head to the cutter-head.

It will be understood that this machine as arranged works automatically. The wheel or cutter-head derives its power from the butter which is forced by the worms through the former and former-head. As 110 the butter issues from the former 17 and former-head 19, it slides over the rolls 20, and pushes the first knife that is nearest to the butter in its path. As this knife is being pushed by the butter, the wheel or cutter-head is rotated thereby. The faster the butter is fed to the worms 18, the faster it leaves the former, and the faster it revolves the wheel or cutter-head, and consequently the wheel cuts the material into lengths or 120 cakes faster.

The size of the cake is reduced to proper weight by a spring plate 19' secured in the outlet of the former-head. This is simply and quickly done by turning the set-screw 19^a.

The butter is forced down from the hopper by two rotary paddles 26 having spring-pressed blades 27. In order to speed the conveyor belt 21 to conform to the feed, a 125 130

shaft 28 has a worm gear 29 which transmits motion to the worm 30 on the shaft which drives the conveyor, and this shaft is driven through a chain 31 from the main 5 drive-shaft 32, as are the shafts 33 which carry the paddles 26.

I claim:

1. An automatic butter-cutting machine including a rotatable wheel or cutter-head, 10 knives pivotally connected therewith which successively come into the path of the butter, means for holding a knife in fixed relation to the wheel or cutterhead during the entire operation of cutting, and means for 15 feeding the butter against the intermittently fixed knife, whereby the wheel or cutter-head is revolved, and the butter is cut into lengths.

2. An automatic butter-cutting machine 20 including a rotatable wheel or cutter-head, knives pivotally connected therewith which successively come into the path of the butter, means for holding a knife in fixed relation to the wheel or cutterhead during the 25 entire operation of cutting, means for feeding the butter against the intermittently fixed knife, whereby the wheel or cutter-head is revolved, and the butter is cut into lengths, and means for heating the knives.

3. An automatic butter-cutting machine 30 including a rotatable wheel or cutterhead, knives pivotally connected therewith which successively come into the path of the butter, means for holding a knife in fixed relation to the wheel or cutterhead during the entire 35 operation of cutting, means for feeding the butter against the intermittently fixed knife, whereby the wheel or cutterhead is revolved, and the butter is cut into lengths, and name- 40 plates secured to the periphery of the wheel or cutterhead and between the knives for imprinting the butter.

4. An automatic butter cutting machine including an automatic feed for the material 45 to be cut, and a wheel or cutter-head carrying pivotally mounted knives which are intermittently fixed and which come in the path of the butter, whereby the wheel is revolved, and the butter is automatically 50 cut into lengths, and name-plates secured to the periphery of the wheel or cutter-head between the knives for imprinting the butter.

5. An automatic butter cutting machine 55 including an automatic feed for the material to be cut, a wheel or cutter-head carrying knives which come in the path of the butter, whereby the wheel is revolved, and the butter is automatically cut into lengths, 60 name-plates carried by the wheel or cutter-head between the knives for imprinting the butter, and means for heating the knives and name-plates.

6. An automatic butter cutting machine 65 including an automatic feed for the mate-

rial to be cut, a wheel or cutter-head carrying knives which come in the path of the butter, whereby the wheel is revolved and the butter is automatically cut into lengths, and means for heating the knives, which includes a hood which encloses a portion of the rim of the wheel or cutter-head for concentrating the heat at such point. 70

7. The combination of a table, standards erected thereon, a shaft supported by the 75 standards, a wheel or cutter-head mounted to turn on the shaft, knife-holders pivotally supported at the rim of the wheel or cutter-head, means for rigidly holding said knives as they pass in the path of the material to 80 be cut, and means for automatically feeding said material, whereby to drive the wheel or cutter-head and cause the knives to cut it in lengths.

8. The combination with a table having 85 rollers and conveyors thereon, a former, a former-head, and means for feeding the material into, and discharging it from, the former-head upon the rollers, of a rotatable wheel or cutter-head carrying pivoted cut- 90. 95

ters, and means connected with each cutter for holding said cutters in fixed relation successively in the path of the fed material whereby the wheel is turned and the material is cut into lengths. 100

9. The combination with a table, standards erected thereon, a shaft extending across from one standard to another, means for holding and adjusting the height of the shaft, a wheel or cutter-head rotatably supported on the shaft, a fixed cam, knife-holders pivoted to the rim of the wheel or cutter-head, cam rollers, and arms, and 105 springs connected with the knife-holders, said rollers in position to be engaged by the cam when in certain positions to provide means for turning the wheel or cutter-head and for cutting the butter into lengths.

10. The combination with a table, standards erected thereon, a shaft extending 110 across from one standard to another, means for holding and adjusting the height of the shaft, a wheel or cutter-head rotatably supported on the shaft, a fixed cam, knife-holders pivoted to the rim of the wheel or cutter-head, cam rollers, and arms, and springs connected with the knife-holders, said rollers in position to be engaged by the 115 cam when in certain positions to provide means for turning the wheel or cutter-head and for cutting the butter into lengths, stops connected with the knife-holders for limiting the movement of the knife-holders in one direction. 120

11. The combination with a table, standards erected thereon, a shaft extending across from one standard to another, means for holding and adjusting the height of the shaft, a wheel or cutter-head rotatably supported on the shaft, a fixed cam, knife-holders piv- 125 130

oted to the rim of the wheel or cutter-head, cam rollers, and arms, and springs connected with the knife-holders, said rollers in position to be engaged by the cam when in certain positions to provide means for turning wheel or cutter-head and for cutting the butter into lengths, stops connecting with the knife-holders for limiting the movement of the knife-holders in one direction, and 10 means for vertically adjusting the shaft which carries the wheel and cam.

12. In an automatic butter cutting machine, a rotatable wheel carrying fixed name-plates on its periphery and knives, the latter pivotally supported, and means for controlling the position of the knife-holders, during the functioning of the knife.

13. In an automatic butter cutting machine, a rotatable wheel carrying name-plates and knives, the latter pivotally supported, means for controlling the position of the knife-holders, and means for heating the knives and name-plates.

14. In an automatic butter cutting machine, the combination with a former, a former-head, and means for adjusting the size of the outlet of the latter, of mechanism for forcing the material to be cut through the former-head, means for cutting the material as it issues from the former-head, and means for heating the knives.

15. Means for cutting plastic material, including cutters, a rotatable wheel, cutters carried thereby and means for feeding the material against the cutters, whereby to cause a successive presentation of cutters for severing the material into lengths, and means for heating the cutters.

16. Means for shaping and cutting plastic material including a rotatable device presenting cutting means in the path of the oncoming material and following cutting means successively to sever the fed plastic material, and means for holding the cutters rigidly during the cutting operation, thus providing an abutment in position to receive the impact of the fed material, whereby the rotation of the device is effected.

17. An automatic butter cutting machine,

including a wheel, cutters carried thereby, a table, a roller journaled in the table in position to cooperate with a cutter in cutting the material into divisions and means for forcing the material under pressure into the space between the table and wheel and 55 against a cutter whereby to turn the wheel and cause the presentation in its turn of another cutter.

18. An automatic butter cutter including a rotatable wheel, a fixed cam, cutters pivoted to the wheel and carrying rollers which traverse the cam, and springs which hold the rollers against the cams during a portion of the rotation of the wheel whereby to hold them in place and which swing the cutters 65 on their pivots and out of the way of the material after the cutting has been done.

19. An automatic butter cutter including a rotatable wheel having a flanged periphery, the flange slotted, pivoted cutter holders 70 extending through the slots, cutters carried thereby and name plates secured to the peripheral flange between the slots.

20. An automatic butter cutter including a rotatable wheel having a flanged periphery, the flange slotted, pivoted cutter holders extending through the slots, cutters carried thereby and name plates secured to the peripheral flange between the slots, arms secured to the cutter holders, and carrying 80 rollers, and a cam and springs for controlling the position and action of the cutter holders and cutters.

21. An automatic butter cutter including a rotatable wheel having a flanged periphery, the flange slotted, pivoted cutter holders extending through the slots, cutters carried thereby and name plates secured to the peripheral flange between the slots, arms secured to the cutter holders, and carrying 90 rollers, and a cam and springs for controlling the position and action of the cutter holders and cutters, and a stop secured to each holder to limit the backward movement of the holder.

In testimony whereof I hereunto affix my signature.

ISAAC C. POPPER.
